UNITED STATES PATENT OFFICE

WILLIAM L. BROWN, OF PHILADELPHIA, PENNSYLVANIA

FENDER IRON

Application filed November 11, 1931. Serial No. 574,310.

My invention relates to fender irons such as are used on barges, wharves and the like and has for its object to provide a fender iron of improved construction better adapted 5 to the exigencies of use than is the case with fender irons now in service. Generally speaking, my invention consists in constructing a fender iron preferably of a resilient ferrous alloy, the fender iron being formed 10 with lateral flanges for attachment to the structure to be protected, connected by an intermediate portion of arch form, in which the metal of the fender iron is so disposed as to be thicker at the central portion of the 15 arch than at the sides of the arch and preferably the thickened central portion of the arch tapers gradually into the sides of the arch. Again, preferably, the disposition of the metal should be such as to form what is 20 in effect an inwardly projecting rib at the center of the arch, with tapered sections extending outward from the rib with diminishing cross section, in which they merge with the base portions of the arch. This construction imparts to the fender iron qualities of a 25 stiff beam, as a result of which impacts against the fender iron are well distributed over the surface to which it is secured, while at the same time the center of the arch against 30 which impacts are most likely to occur is of so massive a construction as to resist effectually forces tending to dent it in and to deform the fender iron. At the same time the resilient character of the metal which I preferably 35 use in the construction of my fender iron permits a certain amount of deformation in the arch at the moment of impact without resulting in a permanent deformation.

By so distributing the metal in the arch 40 that the thickened central portion tapers gradually into the upper side portions of the arch, I materially strengthen the structure against impact stresses coming in a more or less lateral direction against it while the external arch form of the fender tends to guide

any contacting body toward the center of the arch and thus to lessen any impact strains which tend to wrench the fender iron away from the structure to which it is attached.

For some applications it is advantageous 50 to provide a plurality of arch shaped projections constructed as described, which are advantageously spaced from each other by flat portions adapted to rest against the structure to be protected and to serve as a means 55 for securing the fender to the structure additional to the outer flanges.

My invention will be better understood as 60 described in connection with the drawing, in which

Figure 1 is a cross sectional view of a fender iron embodying my invention.

Figures 2 and 3 are similar cross sectional views of modifications of the structure shown in Fig. 1, which also fully embody my invention, and

Figure 4 is a cross sectional view, illustrating a construction in which a plurality of arch shaped projections are formed, spaced from each other by flat portions adapted like 70 the lateral flanges to rest against the structure to be protected.

In the drawing, A, A indicate outwardly extending edge flanges adapted to rest upon and be attached to the structure to be protected. B, Fig. 1, B², Fig. 2, and B³, Fig. 3, represent an intermediate arch-shaped portion of the fender iron, which, as shown in the different views, has exteriorly the form of a segment of a circular cylinder but which 80 may vary in exterior outline so long as a general arch-shaped contour is maintained. C, C, etc., indicates a thickened top portion of the arch, preferably forming, as shown, an inwardly projecting rib connected by gradually tapering sections D, D, which merge finally into the base portions E, E of the arch. The base portions of the side walls of the arch, as indicated at E, E, etc., are much 85 thinner in cross section than the upper por- 90

tion of the arch and may advantageously be approximately the same thickness as the flanges A, A.

It will be obvious that the massing of the metal at and adjacent to the top of the arch and in the flanges and adjacent portions of the base of the arch will give to the fender iron great stiffness as a beam, thus insuring that any impact strain will be taken up by a considerable length of the structure to which the fender iron is attached. It will also be obvious that the mass of the metal at the top of the arch adapts the fender iron to resist the tendency of impact strains to indent or collapse the arch and that the disposition of the metal in the upper part of the arch, as shown, that is, so that the thickened crown of the arch tapers gradually into the side walls, will impart great strength to resist the tendency of lateral impacts to distort or deform the fender iron. The arch shape of the portion of the fender iron which is subjected to impact blows serves to direct any contacting body toward the center and strongest part of the arch and thus to diminish blows tending to wrench the fender iron from the structure to which it is attached, while the tapered cross section of the side walls of the arch makes available the resilient qualities of the ferrous alloy, which I preferably employ, enabling the arch of the fender iron to yield slightly to deforming strains without bringing about permanent deformation.

35 In Fig. 4 I have illustrated a construction in which the fender iron is formed with two arch-shaped projections, each similar in construction to that shown in Fig. 1, the arches being spaced by a flat portion A¹ adapted to rest against the structure to be protected and to serve as do the flanges A, A as a means of securing the fender iron to the structure.

Having now described my invention, what I claim as new and desire to secure by Letters Patent, is:

50 1. A fender iron of a bendable ferrous alloy having lateral flanges adapted to contact with the structure to be protected, and an intermediate arch-shaped portion extending from end to end of the fender iron and which in cross section is thicker at the top of the arch than at the lateral sides connecting the upper portion of the arch with the lateral flanges of the fender iron.

55 2. A fender iron as called for in claim 1, in which the fender iron is made up of a resilient ferrous alloy.

60 3. A fender iron as called for in claim 1, in which the thickened central portion of the arch tapers gradually in thickness as it merges into the side walls of the arch.

65 4. A fender iron as called for in claim 1, in which the metal forming the upper portion of the arch is so disposed as to form an inwardly projecting rib at the top of the arch

connected by intermediate tapered sections to the portions of the arch forming its base.

5. A fender iron as called for in claim 1, having a plurality of arch-shaped intermediate portions.

6. A fender iron as called for in claim 1, having a plurality of arch-shaped intermediate portions spaced from each other by flat portions adapted to lie in contact with the structure to be protected.
